ELECTRIC COUNTING DEVICE

Ingvald Julius Alnaes, Oslo, Norway, assignor to
 I. Alnaes A/S, Oslo, Norway, a corporation of
 Norway, and Ingeniørforretningen Atlas A/S,
 Oslo, Norway, a corporation of Norway

Application March 6, 1939, Serial No. 260,152
 In Norway February 11, 1938

1 Claim. (Cl. 235—92)

The present invention relates to electric counting devices for the counting of the revolutions of a shaft, in which device the counting is effected by means of electric impulses, the number of which corresponds to the number of revolutions of the shaft. The device is particularly, but not exclusively, adapted for use in connection with ship logs.

In accordance with the invention, an electric coil which is fed with an alternating current and is provided with a core of ferromagnetic material is arranged in connection with the shaft, the revolutions of which are to be counted, the magnetic resistance (reluctance) of the said core being varied in time to the revolutions, in order to vary the inductive resistance of the coil and thereby give rise to electric impulses which may be counted.

According to one feature of the invention the core is made in the form of a horse shoe the free ends of which are shaped according to cylindrical surfaces, and the variations of the magnetic resistance of the core is effected by periodically short circuiting the core by means of a member of magnetically conductive material, the said member rotating with the shaft and having a cross section in the form of a segment of a circle with the same axis as the cylindrical surfaces of the core ends.

According to a further feature of the invention the variation of the inductance of the coil is effected by moving the core relatively to the coil in time to the revolutions of the shaft, the revolutions of which are to be counted. The core hereby suitably is moved into and out of the central cavity of the coil and, if desired, through the same, the core being of horse shoe form with parallel legs which may be straight or formed according to an arc of a circle. In the first case, the movement of the core is in the direction of the length of the legs, and in the latter case as an oscillation about an axis in the centre of the arc of the circle according to which the legs are formed. Where the core is to be moved in a fluid, which for instance is the case when the counter is to be used in connection with ship logs, the coil conveniently is placed fluid-tightly in a housing in such a manner that the central cavity of the coil is in free communication with the fluid. In such cases the core conveniently is surrounded by a sleeve or layer preventing the fluid from penetrating to the core or in between the laminations or wires of the core and giving rise to corrosion.

The coil suitably may be so arranged in the

5 circuit of the counting device that the coil constitutes one branch of a Wheatstone bridge which is in balance when the magnetic resistance of the coil core has a maximum.

In the accompanying drawings some embodiments of the invention are illustrated schematically. Figure 1 shows the circuit arrangement of the counting device. The Figures 2 to 6 show the parts of the device which are in direct connection with the shaft, the revolutions of which are to be counted. Figure 2 is a vertical section through an embodiment and Figure 3 a horizontal section through the device on the line III—III in Figure 2.

Figure 4 is a vertical section on the line IV—IV in Figure 5, through a further embodiment wherein the core is made with straight legs.

Figure 5 is a horizontal section through the same device on the line V—V in Figure 4.

Figure 6 shows one embodiment wherein the core legs are formed according to an arc of a circle, the figure showing a section through the axis of one leg of the core.

In Figure 1, 1 is the coil, the inductance of which is to be varied in time to the revolutions to be counted and which constitutes one branch in the Wheatstone bridge. The opposite branch of the said bridge is constituted by a coil 2, the inductance of which is constant and equal to the inductance of coil 1 when the core of the same has its maximum magnetic resistance. A constant alternating voltage is applied to the bridge through the transformer 3 across the terminals 4. In the diagonal of the bridge a counting instrument 5 is inserted in series with rectifiers 6 and 7.

The counting instrument 5 may be any conventional device actuated by the current pulsations to register the number thereof. Such an instrument might well be of the type shown in the patent to F. C. Harris, No. 1,459,730, patented June 26, 1923. By variation of the inductance of the coil 1, the bridge is brought out of balance and a current impulse will flow through the instrument which, in a manner known per se, is arranged for the counting of current impulses. As the inductance of the coil 1 varies between a maximum and a minimum value in time to the revolutions of the shaft, the instrument 5 will indicate a number corresponding to the revolutions of the shaft and which for instance by ship logs is a measure of the distance which the ship has travelled.

In the Figures 2 and 3 the coil 1 is arranged on one leg of a horse shoe core 8 of ferromagnetic

material, for instance laminated sheet iron. 9 designates the short circuiting member which rotates with the shaft and is so arranged as to periodically short circuit the air gap between the legs of the core 8. The short circuit member 9 is made of magnetically conductive material and is arranged on a circular disc 10 which, by means of gears 11 (only shown in part) are driven from the shaft 12. In order to obtain a smooth variation of the magnetic resistance of the core 8, the member 9 is made in the form of a segment of a circle and the free ends of the legs of the core 8 are shaped according to cylindrical surfaces with the same centre as the member 9. The entire coil and core arrangement is located 15 in a housing 13 of non-magnetic material, and is, by 14, connected to the log proper (not shown). In order to prevent the coil 1 from being affected by the sea water flowing through the log, the housing 13 is by means of a wall 15 divided into two rooms, of which the room containing the coil 1 is filled with insulation material. In order to prevent the generation of eddy currents in the wall 15, the same is provided with a slot 16 extending between the legs of the core 8.

In the Figures 4 and 5, 1 designates the coils of which one may be arranged on each leg of the horse shoe core 8. As shown in Figure 6, only one coil 1 may be used, this coil then being placed on one leg of the core. The coils are embedded in insulation material 17 and located in a housing 13 of non-magnetic material, using fluidtight packings 18 and protecting sleeves 19, the inner cavity 20 of each coil being coaxial with an opening in the housing 13. The core 8 operates in cavity 20. By means of couplings and gears (not shown), the core 8 is so connected to the shaft 12 the revolutions of which are to be counted, that the core is moved into and out of the coils 1, timed corresponding to the number of revolutions of the shaft. In order to support the coils

5 against electromagnetic forces and against possible fluid pressure in the space in which the core is moved, the protecting sleeves 19 surrounding the coils are made of rigid material and are held by means of a yoke 21 secured to the housing by means of bolts 22. A spherical segment pressure member 23 is arranged between the sleeve 19 and the yoke 21. The core 8 is surrounded by a fluid tight insulation 24.

10 What I claim is:

A device for counting the revolutions of a rotating shaft especially for use in connection with ship logs, comprising in combination, a movable magnetically conductive member adapted to be moved through successively recurring cycles by the shaft the revolutions of which are to be counted, two systems of windings constituting respectively two adjacent branches of a Wheatstone bridge circuit, the reactance of one of the windings being variable, a transformer having a split secondary the parts of which constitute the two remaining branches of the Wheatstone bridge, a source of alternating current of constant frequency for supplying the primary of said transformer, and a series arrangement comprising a rectifier, an impulse counter, and a second rectifier connected in series in the order mentioned, and constituting together the diagonal of the Wheatstone bridge arranged between the transformer secondary junction and the junction of the two winding systems, the variable one of the said two systems of windings being so positioned in relation to the said movable magnetically conductive member that the inductive reactance of the same is varied in time to the movements of said member, the two systems of windings being so dimensioned relatively to each other that the bridge is in a state of balance when the inductive reactance of the variable system is at a maximum.

40 INGVALD JULIUS ALNAES.
